[57] ABSTRACT

The present invention is directed to an indoor escape device which allows the evacuees to pass through a manhole in a slab by which two stories are separated thereby escaping swiftly to a safety story or zone one after another without going from the indoors to the outdoors.

INDOOR ESCAPE DEVICE

BACKGROUND OF THE INVENTION

The present invention relates to an indoor escape device, and more particularly to an emergency installation which enables the evacuees to escape from dangers such as fire, smoke, gas or water leakage, and ruffians.

The escape devices heretofore found best in buildings have been emergency stairs mounted on the external wall of the buildings, or an emergency rope, ladder, and chute or the like. No matter where the emergency stairs are located, in an emergency the evacuees who are in an area far away from the stairs have a hard time to reach them. Thus, in an emergency the lives of evacuees who must go to the location where the stairs are positioned are jeopardized. If an emergency occurs in an area close to the stairs, it is even worse due to the possible combination of unfavorable conditions such as interruption of electric current, fullness of smoke in addition to the instant accident. The emergency ladder or the chute must be taken out from a housing or container mounted on the wall at the window and, after seeing if the site is safe, hung out the window. This requires much time and trouble. Furthermore, if the building is extremely high and there is a large number of evacuees, the use of such ladder or chute is limited to the least extent.

The present invention involves a manhole provided in a slab between two stories or a single veranda slab to give easy access to the upper or lower story or floor, a shell received in the manhole, a cover member mounted on the manhole, an extensible elevating member arranged within or adjacent the manhole not only for lowering but also for lifting the evacuees.

The present invention is characterized in that the cover mounted on each of the slabs between the two stories is opened to stretch the elevating member from the manhole to the next floor thereby allowing the evacuees to escape readily from danger.

According to the present invention, there is no need of massive installations, as for example, emergency stairs attached to the external wall of the building, and the arrangement may be provided in suitable numbers anywhere on the slab, floor, or the veranda of the building to improve emergency capability so that more evacuees can safely, readily, and quickly escape to a safety zone on another floor, in contrast to the prior art in which the emergency exit is limited. In addition, in accordance with the present invention, the evacuees can escape from danger within the building by promptly pulling down a shutter to prevent a fire blaze or smoke from spreading without requiring any care-taker, or watchman.

These and other objects and advantages of the invention will be apparent from the following description and accompanying drawings in which:

BRIEF DESCRIPTION OF THE DRAWINGS

FIG. 1A is a sectional view of floor and ceiling slabs incorporating one embodiment of the present invention;

FIG. 1B is a sectional view of a veranda in which the present invention is embodied;

FIG. 2A is a sectional view showing cover members in one form, which are mounted on each of the floor

and ceiling slabs so as to be coplanar to the surfaces thereof;

FIG. 2B is an enlarged, detailed view showing a lock structure for the cover member;

5 FIG. 2C is representation showing a hanger connecting an upper plate to a lower plate of the cover member;

10 FIGS. 3A to 3D are sectional views showing another embodiment of the invention which is adapted to open the cover member for the ceiling in cooperation with the floor cover member;

15 FIG. 4A is a plan view of a modified form of each of the cover members and a manhole through the floor or ceiling;

15 FIG. 4B is a view in vertical section taken along the line 4B — 4B of FIG. 4A;

20 FIG. 5 is a sectional view of the floor and ceiling incorporating a further embodiment of the invention in which a chair-like slide is provided to carry the evacuee;

25 FIG. 6 is a sectional view of the floor and ceiling incorporating a still further embodiment of the invention in which the cover member is adapted to prevent it from its pivotal movement at a desired angle;

25 FIG. 7 is a sectional view of a shell mounted within the manhole in both the floor and ceiling;

30 FIG. 8A to 8D are sectional views of an extensible shell in a modified form, which is adapted to adjust its length to the distance between the floor and ceiling slabs;

35 FIGS. 9A to 9C are sectional views of an extensible shell in another modified form, which is constructed in consideration of fire proof and heat resistance;

35 FIGS. 10A to 10C are sectional views showing an extensible elevating member provided within or adjacent the manhole;

40 FIGS. 11A to 11C are sectional views of the extensible elevating member provided in an area other than the manhole;

40 FIGS. 12A and 12B are sectional views of the floor and ceiling incorporating other embodiments of the invention in which extensible elevating member provided in the manhole;

45 FIGS. 13A to 13G are representations showing the extensible elevating member when it depends from a stator;

45 FIG. 14 is a sectional view of the manhole slab incorporating an additional embodiment of the invention in which the cover member disposed in ceiling member is adapted to be opened by operation of the elevating member; and

50 FIG. 15 is a schematic view showing the total escape arrangement which further includes a locking device, alarm device, fire alarm, and fire or smoke sensor.

DESCRIPTION OF THE PREFERRED EMBODIMENTS

50 Referring to FIGS. 1A and 1B, numeral 1 is a manhole which is bored through a floor slab 2 or a ceiling slab 3 disposed thereunder and any number of which may be provided at any place as desired, for instance, a corridor, room, or veranda (FIG. 1B). The slabs are bored so that the openings 1 are in alignment with each other whereby the evacuees can escape from danger to the other story without going outdoors.

55 A cover member 4 is pivotally mounted on the floor slab 2 by suitable means such as a hinge 7 or the like

at a pivot axis 9 so as to cover the manhole 1 on which a flanged frame 6 is mounted. Similarly, a cover member 5 is also hingedly mounted on the ceiling slab 3 so as to cover the manhole 1 on which a flanged frame 8 is mounted.

In FIGS. 2A and 2B, the floor cover member 4 is adapted to be in a plane coplanar to the surface of the floor 2 and is mounted within the flanged frame 6 over the manhole 1. As best shown in FIG. 2B, a handle 10 is provided to engage a lock shaft 11 and is embedded within the cover member at its corner when it is not in use. With this arrangement, the cover member is prevented from being opened unless an emergency arises.

FIG. 2C shows a modified form of the cover member 5 used to cover the manhole 1 in a veranda which has no space and by which the evacuee can escape to the floor without passing the manhole in the ceiling. In this instance, the cover member 5 is arranged to include an upper plate and lower plate which is connected by a rope or chain 12 to the upper plate so that the cover member is readily opened by cooperation of the two plates.

In FIGS. 3A to 3D, the floor and ceiling cover members 4 and 5 are in cooperative relationship with each other to allow the floor cover member to open with the ceiling member. To this end, a spring actuated rod 13 is vertically interposed between the two cover members. The floor cover member 4 is held against the bias of the spring actuated rod 13 by engagement of suitable means with the cover member at its edge. The spring actuated rod 13 is adapted at its lower end to abut against a retainer 15 which is normally clockwise biased and engages a stopper 14 mounted on the ceiling cover member 5. The rod 13 is allowed to upwardly project from the floor slab 2 by opening the cover member 4 while the lower end of the rod is away from the retainer 15 to allow it to rotate and to be disengaged from the stopper 14 thereby rotating and opening the ceiling cover member 5.

In FIG. 3B, a suspension rod 16 is shown to depend on the floor cover member 4 and is engaged at its lower end by a locking device 17 such as a catch latch or the like mounted on the ceiling cover member 5. Opening of the cover member 4 lifts the rod 16 to allow the rod to be disengaged from the device 17 thereby opening the ceiling cover member 5.

Referring to FIG. 3C, lever means comprises an arm pivotally mounted on the floor cover member 4, a spring interposed between the arm and the flanged frame to counterclockwise urge the arm, and a lever 18 pivotally connected to the arm and held against its counterclockwise movement by engaging its hooked end with a pin 19 mounted on the ceiling cover member 5. Opening of the cover member 4 allows the lever 18 to counterclockwise move thus disengaging the hooked end from the pin to open the ceiling cover member 5.

As shown in FIG. 3D, an arm 20 is mounted on each of the floor and ceiling cover members 4, 5 so as to slidably carry a swingable rod 21. A link is provided to swing about its axis between the swingable rods at the end thereof. With this arrangement, the two cover members 4, 5 are cooperatively moved and opened.

Referring to FIGS. 4A and 4B, the cover member for both the floor and the ceiling, and the flanged frame are square shaped while the manhole in the floor and the ceiling is circularly shaped. In order to receive a

square cover member, it is necessary to provide a corresponding square recess for the floor, the side of square recess making the diameter of a circular manhole. As shown, this arrangement provides a step portion so that it is convenient for the evacuee when passing through the manhole. The circular manhole is preferable to the square manhole since it will economize a space with the same effective area and facilitate the action of the evacuee.

10 FIG. 5 shows the opening 1 of the floor is provided with a chair-like slide 22 mounted on the flanged frame 6. Having the evacuee sit down on the slide 22 facilitates his action and dissipates his fear. This slide may be rigidly mounted on the flanged frame or rotatably 15 mounted to allow it to be received in the space between the slabs; otherwise it is detachably mounted to allow it to be stored in a certain place.

10 In FIG. 6, the floor cover member 4 is shown as having a ratchet mechanism. The ratchet mechanism comprises a ratchet wheel 23 and a detent 24 so that the cover member is prevented from its pivotal movement at a desired angle. If necessary, a rope 25, or cord, wire may be attached to the detent 24 so that the cover member is shut by pulling the rope to release the detent 25 upon reaching the next story to intercept smoke or fire.

A shell 26 shown in FIG. 7 is adapted to be received in the manhole 1 in the floor and ceiling slab to cover them and partition off the space between the slab so that a fear of the evacuee is also dissipated to facilitate 30 his action.

A modified form of the shell is also shown in each of FIGS. 8A to 8D. In FIGS. 8A and 8B, a plurality of frame 27 are coupled to one another to form a unitary shell. The number of frames may be increased or decreased in accordance with the distance between the slabs. The shell 26 shown in FIGS. 8C and 8D is made of corrugated metal or plastic sheet 28, or elastic sheet so its length can be adjusted in accordance with the distance between the slabs.

40 A further modified form of the shell 26 is illustrated in FIGS. 9A and 9B. As shown, a coating material 29 such as fire-proofing material or heat-resisting material is coated at the external or the internal surface of the shell to protect the evacuee against fire or smoke if flames spread. The shell 26 (FIG. 9C) is provided with buffer member 31 integrated therewith to protect the evacuee from a scratch and bump when he is escaping through the manhole.

50 Various forms of guide means 32 for leading the evacuee from one story to another are shown in FIGS. 10A to 10C. They are all adapted to be extensible and collapsible in use and non-use and received in the space defined by the shell 26 and the cover members 4, 5. In FIG. 10A, guide means 32 is shown as a rope. In FIGS. 55 10B and 10C, guide means are shown as a rope, ladder, and a collapsible stair, respectively.

FIGS. 11A to 11C show examples where guide means are stored in a suitable area other than the space defined by the shell and the cover members. The guide means in FIG. 11A is received in a recess 33 in the floor slab. In FIG. 11B, the guide means is stored in a recess in a partition wall of the story where the manhole is bored through the floor slab thereof. In FIG. 11C, the guide means is received in a ceiling slab above the floor of the story. All guide means are adapted so that the leading end each of them is secured to a retainer ring 36 fixed to the recess 33 or housing. In use, the guide

mean is taken out from the recess and is lowered upon opening the cover member. The guide means shown in FIG. 12A is received in the cover member 4 which consists of an upper plate and a lower plate 33. In use, the lower plate is opened in association with the upper plate. As shown, numeral 37 designates a grip which the evacuee grasps before taking hold of the guide means. The guide means illustrated in FIG. 12B is disposed between the cover member 4 and a keeper plate 33 one end of which is mounted to the cover member. In use, the cover member is raised to a position where the guide means is readily taken out and lowered.

One or more arc-shaped fittings 38 see FIGS. 13A and 13B are mounted above the opening in the floor 2 to readily hang guide means therefrom when in use. 15 Outside of emergencies, the guide means may be stored in the recess adjacent the manhole. As shown in FIG. 13C, the arc-shaped fitting 38 may be mounted on any one of the sides of the manhole to hang the guide means therefrom. Slidable or rotatable bar 39 may be provided, as shown in FIGS. 13D, 13E, and 13F under the cover member to the hang guide means therefrom. In FIG. 13G, the bar 39 is mounted parallel to the cover member and is adapted to hang perpendicular to the cover member when the cover member is opened. The bar 39 shown in FIG. 14 is adapted to open the ceiling cover member when it is operated. A projection 40 is mounted at the lower end of the bar and received in an elastic tongue 41 which engages a retainer 42 mounted on the cover member so that if the bar is actuated to allow the projection 40 to be away from the tongue 41 to slide it, the cover member 5 is opened upon disengagement of the tongue with the retainer.

The indoor escape system may be required to include many type of control means, as shown in FIG. 15, such as a locking device for maintaining closure of the cover member, alarm device, fire alarm, fire or smoke alarm and any type of electric device electrically connected to a power board in a control room of the building. The alarm device and electric devices provide functions, such as, of promptly giving alarm and/or warning for a fire or smoke occurred to a control room or zones other than a spot suffering from an accident in the building and/or of disengaging said escape unit from its locking engagement by means of a control board in said control room.

It is to be understood that the embodiments of the invention which have been described are merely illustra-

tion of the principals of the invention. Numerous modifications and changes may be made without departing from the true spirit and scope of the invention.

What is claimed is:

- 5 1. An escape system for positioning between the floor of one story of a building and the ceiling of a story below the firstmentioned story, said system comprising: an escape means including a first frame means adapted to be positioned in a hole in the floor of the one story and a second frame means adapted to be positioned at the other end of said hole in the ceiling of the story below said firstmentioned story, an adjustable bellows type shell means extending between said first and said second frame means forming an escape passage for an evacuee, a cover member positioned over at least one of said frames for closing the hole when the system is not in use, and an escape unit secured adjacent said escape means and adapted to extend through at least part of said shell means when said cover member is open for use by the evacuee in passing through said escape means.
2. An escape system as claimed in claim 1 in which said shell means has a coating of a heat resistive material on the exterior thereof.
3. An escape system as claimed in claim 1 in which said shell means has a coating of an elastic buffer material on the interior surface thereof.
- 30 4. An escape system for use in a multi-story building comprising a plurality of escape means adapted to be positioned between the floor and ceiling of each of at least the majority of said stories, each of said escape means including a first frame means adapted to be positioned in a hole in the floor of one story and a second frame means adapted to be positioned at the other end of said hole in the ceiling of the story below said firstmentioned story, an adjustable bellows type shell means extending between said first and said second frame means forming an escape passage for an evacuee, a cover member positioned over at least one of said frames for closing the hole when the system is not in use, and an escape unit secured adjacent said escape means and adapted to extend through at least part of said shell means when said cover member is open for use by the evacuee in passing through said escape means.
